UNITED STATES PATENT OFFICE.

ARMIN TETÉLENI, OF BUDAPEST, HUNGARY.

DRIVING OF TOOL-MACHINES, ESPECIALLY FOR VARIABLE WORKING RESISTANCE.

1,369,853.

Specification of Letters Patent.

Patented Mar. 1, 1921.

Application filed November 26, 1917. Serial No. 204,132.

To all whom it may concern:

Be it known that I, ARMIN TETÉLENI, a subject of the King of Hungary, residing at Budapest, Hungary, have invented a new 5 and useful Improvement in the Driving of Tool-Machines, Especially for Variable Working Resistance, of which the following is a specification.

Most of the usual machine tools driven, 10 *e. g.*, by eccentrics, levers and the like, with reciprocating tool (plate shears or cutters, punching machines, presses, etc.), which perform work on blanks with variable working resistances, have the defect that 15 they do not take into account in different cases the actual amount of resistance work of the blank or the continuously varying values of the same in the different phases of the working stroke, but are designed 20 rather on the basis of the maximum strain for the entire working stroke, and they must therefore be given a working capacity which is too high in proportion to the total working resistance which must actually be 25 overcome. This results in machine parts of more than necessary strength and hence in high cost of construction. Moreover, the waste of power, in which the excess means nothing more than an unnecessarily high 30 and harmful acceleration of the mass, renders the operation far too expensive.

It is true that drives have heretofore been devised which show a certain tendency to take the varying working resistances in one 35 direction or the other into account for the transmission of movement. But these drives are, on the one hand, relatively complicated, while, on the other hand, they can by no means be said to represent a systematic adaptation—*i. e.*, an intelligent adaptation 40 to each phase of work, allowing in every direction for the requirements in each individual case—to the continuously varying unequal distribution of the factors 45 (power and stroke) of the work actually required for the entire working stroke. Still less can they be said to represent a predetermined intervention in the ratios of the 50 working factors at any given periods of stroke or time in the process of work to the end of influencing the same at will in the most varied cases.

Thus, for instance, drives for riveting machines and the like have become known 55 in which the ratio of transmission of the driving shaft to the tool holder shows its

maximum value at the end of the working stroke, and in which the speed and driving power vary in inverse ratios. The latter, however, has been the case only in a very 60 general sense—*i. e.*, without any possibility of taking into account the so-called diagram of work at given points of the process of work. Still less has it been possible to exercise an intervention, such as mentioned 65 above, in any given phase of the work and in any desired manner.

These machines, therefore, (with the single exception of the known adjustability 70 of the working stroke by radial displacement of the driving pin) lack the possibility of allowing in one and the same machine for the greatly varying cases of working, such as result from the different kinds of blanks —*i. e.*, the nature of the material, dimensions, etc.—, hence the different behavior 75 of the same under the tool, according to which it becomes necessary to reckon with entirely different conditions of accumulation (or upsettings) of the material, etc., 80 and hence with entirely different values of the working resistance in each case. In special cases it is also necessary to exert an influence, corresponding exactly to practical 85 requirements, upon the course of the working factors with regard to any given point between the beginning and the end of the stroke.

According to the invention a drive is created which is capable of meeting perfectly 90 and in every way the practical requirements in all the above mentioned respects. The essential features of the invention, or the considerations upon which it is based, will first be explained with the aid of the accompanying drawings, in which—

Figure 1 is a diagram representing the resistance of the work piece considered as a function of the time.

Fig. 2 is a diagram representing the resistance of the work piece considered as a function of the work stroke.

Fig. 3 shows an embodiment of the invention, as applied to a shears.

Fig. 4 is a diagram illustrating one 105 method of determining the form of a groove in the tool holder adapted to coöperate with a driving element carried by a rotating driver, in accordance with the principle of the invention herein disclosed.

Fig. 4^a is an auxiliary figure, to be considered in connection with Fig. 4.

Fig. 5 is a diagram illustrating a method of determining a groove or slot of a somewhat different form, a portion of which controls the return stroke of the tool holder, as well as a part of the work stroke, the work holder and driving element being the same as in Fig. 4.

Fig. 5^a is a diagram illustrating a method of determining a form of groove or slot in 10 a work holder, to coöperate with a driving element carried by a swinging driver.

Fig. 6 is a diagram illustrating a method of determining the forms of slots, similar to that of Fig. 5, but adapted to increase 15 the ratio of driver movement for the working stroke, with respect to that for the return stroke.

Fig. 7 illustrates a modification of the invention, as applied to a shears, in which a 20 secondary swinging driver or transmission element is introduced between the primary rotating driver and the tool holder.

Figs. 8 and 9 are diagrams illustrating methods of determining the forms of 25 grooves or slots to coöperate with driving elements, in accordance with the principle of the invention, when applied to a mechanism of the form shown in Fig. 7.

Fig. 10 illustrates the variation in the 30 effect produced upon a tool holder by a variation in the form of slot which coöperates with the driving element on the secondary transmission element.

Figs. 11 and 12 are details, illustrating a 35 practical means of substituting a slot of one form for one of a different form.

Fig. 13 shows an embodiment of the invention, in which a plurality of tool holders of a universal machine may be driven by a 40 common, swinging transmission element, which is itself driven by the rotary driver.

In Fig. 1 the curve P represents the resisting power of the blank as a function of the time t of the working stroke, while in 45 Fig. 2 the curve P' represents said power as a function of the length of the working stroke l , the lines of the time and length of stroke being expediently drawn in the actual direction of the latter, namely, vertically. In the example chosen the work to be performed is separation of material (punching, perforating, cutting or shearing), and the diagrams, known or obtainable by experiments, are partly drawn on 50 an exaggerated scale for the sake of clearness. In many cases, especially for the perforation of metals, the course of the curve P' , for instance, is such that it first rises slowly, then very rapidly owing to the accumulation of the material, reaching its maximum about at the point 7 of the length of the stroke, corresponding to half the time (or duration) of the stroke, then sinking again very rapidly, at first much more 55 rapidly than it had risen before reaching

the maximum, but then, in the vicinity of the line 1, descending in a very flat long-stretched curve to the 0-value at the end of the stroke. In these cases therefore the shape of the curve comes to be perfectly 70 asymmetric. For graphic considerations (i. e., in order to render the below described method of construction of the transmitting mechanism of the invention more comprehensive), we will take for an example the 75 symmetric form of the diagram of forces of the working resistance, which is the simple theoretic form, but in many cases also essentially the correct practical form. This is however immaterial as far as the invention 80 is concerned, since the latter, as will be seen from the following explanations, is applicable in the same manner to cases of any given resistance curves.

It is obvious that in Fig. 2

$$\int_0^{l_1} P'dl,$$

i. e., the area $O-P'_{\max-13}$, represents the diagram area of the greatly variable working resistance, i. e., the work to be overcome by the tool in the course of a working stroke. A reciprocating movement is imparted to the tool holder in a known manner by a driving device rotating at uniform peripheral speed and power, or in certain cases oscillating (eccentric pin of a driving wheel, crank pin, eccentric, rocking hand-lever, etc.,) by means of one or more suitable transmission devices. In order to render the useful work perfectly economic in accordance with the purpose of the invention, we must first take as a standard for the uniform work of the driving device for that 90 part of its rotation or oscillation (working or forward stroke) which corresponds to the working stroke, the area of the diagram of work compensated in a rectangular quadrangle by the dot-and-dash line e' (in the 95 manner indicated by hatching), 100

$$\int_0^{l_1} P'dl = el \text{ or } es$$

respectively, in order to impart to the driving device, when the length of the curve of its forward stroke is s , for instance, the circumferential power X to be determined from the equation $el = X.s$. The area el shows the great economy over former machines in which the driving work was equal to $P'_{\max-1}$. 115

According to the invention the following requirement is made for the power to be furnished by the tool holder in each case 120 and for the course of the stroke of the same:

With a given constant work of the driving device the tool must overcome in each unit of time the respective momentary variable resistance with the same amount of work in 130

all cases. Let the time of the stroke t (Fig. 1) or the length of the curve of the forward stroke of the driving device be subdivided *e. g.*, into 13 equal parts Δt . For each part 5 Δt the same 13th part of the area el (Fig. 2) is available for the work. Consequently the diagram area

$$\int_0^{13} P'dl$$

10 (Fig. 2) is to be divided into 13 equal parts, while the parts

$$\Delta l', \Delta l''_2 \dots \Delta l'_{13}$$

15 of the line l of the stroke, as distinguished from the absolutely equal parts Δt of the time of stroke, will of course come to be unequal owing to and in accordance with the variation of the resisting forces (curve 20 P'), decreasing or increasing in inverse ratio from the latter. In other words,

$$P'\Delta l' = \text{const.} = \frac{el}{x}$$

25 where x designates the number of parts Δt of the time of stroke. In the foregoing example $x=13$.

This unequal division of the stroke l may be determined in the manner indicated in 30 Fig. 1: At each point 1, 2, 3, etc., a given constant, *e. g.* p (proportional to the above mentioned constant $\frac{el}{x}$) is divided by the 35 corresponding power P_1, P_2, P_3, P_4 , etc., the result being the ordinates $\Delta l_1, \Delta l_2$, etc. The curve Δl (Fig. 1) therefore shows the course of the different parts of the stroke required. Instead of determining the 40 values sought at the end 1, 2, 3, etc., of each section Δt , they may also be determined in the middle of the same taking the mean forces into account. These are then transferred in Fig. 2 in the respective ratio upon the line l .

45 The tool must therefore exert during the equal parts of time of the forward stroke of the driving device successively the respective forces P_1, P_2 , etc., according to Fig. 2, which accord with the forces P_1, P_2, P_3 , etc., 50 at the points 1, 2, 3 ... of Fig. 1, describing the corresponding partial strokes $\Delta l'_1, \Delta l'_2$, etc.

55 It is in accordance with this requirement that those parts are formed and dimensioned, according to this invention, which serve to transmit the work of the driving device to the tool holder. In the practical construction, the frictional losses etc., *i. e.*, the mechanical efficiency of the gearing, 60 must of course be taken into account.

For the purpose of the variable transmission in question any positive paths and types of gears, not new in themselves, (*e. g.*, elliptical toothed gears, etc.,) may be used. According 65 to one form of construction of the

invention, however, oscillating crank gear, for instance, or in some cases rotating crank gear may be employed which is simple and expedient; but, as distinguished from known constructions, the link slot or the 70 groove of the respective loop does not have the shape of a straight line but that of a curve which corresponds to the variable transmission determined in the manner stated on the basis of the diagram of work 75 of the resistance of the blank or corresponding to some additional intervention which may be desired.

By employing a suitably shaped curved slot or the like, it becomes entirely possible 80 to insure or subsequently allow for any ratios that may be temporarily required in a machine tool. For in order to meet the requirements with one and the same machine at all times, even when the conditions of 85 work vary considerably (blanks of different materials and different dimensions), the curved slot or curved groove, etc., is furthermore preferably formed, according to the invention, in an exchangeable part of 90 the oscillating lever which transmits the work thereby rendering it possible, provided a supply of such different parts is kept on hand, to meet the most varied conditions without taking the machine apart—*i. e.*, to 95 render one and the same machine serviceable for a long series of apparatus of the most varied types, which would otherwise have to be represented by as many different machines.

100 In addition to the foregoing, the invention admits of an arrangement whereby the above mentioned transmission member, hereinafter called the primary member, connected with the driving device, is enabled to act 105 upon the tool not only directly but also by means of one or more additional transmission members (secondary, tertiary, etc.,) of the same or of a different kind. Through such an additional member it becomes possible to influence or supplement at will according to requirements the action of the primary member for any part of the forward or return stroke, thereby meeting the 110 most varied practical conditions in special cases.

115 It is obvious that owing to the employment of a secondary, etc., member in combination with the above mentioned exchangeability of the curved slot (applicable according to circumstances to the primary or the secondary member or to both) a practically unlimited number of special cases of working with one and the same machine may be considered.

120 The invention also affords the possibility of realizing another moment in a much more favorable measure than heretofore, especially in the case of machine tools for taking off chips (or cuttings), namely the tend- 125

ency, not new in itself, to shorten the return stroke. The usual ratio between the working stroke and the return stroke is about 7:4 with the known rotary link motion (*Umdrehorschleife*), and about 5:2 with the oscillating link motion (*Schwingschleife*) with straight slot, while the theoretic maximum ratios attainable are about 2:1 and 3:1 respectively. (See "Aufgaben und Fortschritte des Deutschen Werkzeugmaschinenbaus" (Problems and Progress of German Machine Tool Construction) by Friedrich Ruppert, Berlin, 1907, page 95.) By means of the below described proper choice of the 15 curved slot or curved groove according to the invention and of the remaining requirements of construction in the meaning of the invention, a much more favorable ratio between the return stroke and the working 20 stroke is attainable, so much so that the relative amounts of the respective values of the forward and return strokes are limited only by the feasibility of practical execution, but by no means by fundamental difficulties.

The invention, which embodies further advantages hereinafter described, is illustrated diagrammatically in Figs. 3 to 13 of the accompanying drawings, showing a few 30 examples of construction.

According to Fig. 3, which shows a general arrangement of the simplest embodiment of the invention, applicable, *e. g.*, to a cutter (or shears), a slot 4 is formed in the 35 rocking lever 2 carrying the movable shear blade 1, which lever is rotatable about the shaft 6 mounted in a frame 3 which receives the fixed shear blade. In said slot 4 engages the eccentric pin 5 of the driving 40 wheel 7 or similar device (crank, rocking lever, etc.,) mounted at 8. The curve of slot 4 is constructed on the basis of the diagram of work in a manner to be hereinafter described. The positions 4' and 4'' of the 45 slot, drawn in dotted lines, correspond respectively to the position of the same at the end of half a rotation of the driving pin 5 and at the end of the working stroke. The short part of the arc between the points R 50 and O corresponds to the duration of the return stroke.

As regards the mode proper of construction of the curved slot, curved groove, etc., on the basis of the above mentioned diagram of work, two methods in particular 55 present themselves. In order to determine the different points of the curve, either the different forces P'_1 , P'_2 , etc., (Fig. 2) or the partial strokes $\Delta l'_1$, $\Delta l'_2$, etc., may be considered. Let us assume, for instance, according to Fig. 4, which shows the method of construction of the geometric middle line 60 of the link on a larger scale, that in the driving circle (or travel circle) M (circular path of the eccentric driving pin rotating

at a constant speed), the greater part of which is subdivided into a number of, *e. g.*, 13, equal parts, the part 0-13 of the arc corresponds to the forward stroke and the part 13-0 to the return stroke. According to the 70 first mentioned method it is necessary to determine for each point 1, 2, 3 . . . 13 of the travel circle the corresponding point of the curve which at the moment when the link is in engagement with the driving pin at that 75 point produces in the tool 1, in accordance with the ratio of transmission, the corresponding power P'_1 , P'_2 , etc., on the basis of the diagram of work. The mean arc of oscillation of said tool is designated by B (Figs. 80 3 and 4), while the angle of deflection of the lever carrying the tool (not shown) and rotatable about the axis A is designated by α . On the circle B is seen the part of the arc 0-13 which corresponds to the stroke and 85 which on the basis of the diagram of work is subdivided into the required number of unequal parts corresponding to the different values Δl .

The different parts of the slot curve 90 would then have to be determined in the following manner:

In Fig. 4^a, let the point 3 be some point on the travel circle M (Fig. 4) the radius of which is designated by r . r_1 is the line 95 which connects the point 3 with the axis of oscillation A (Fig. 4)—*i. e.*, the radius of oscillation of the part k , corresponding to said point 3, of the curve sought. The force P'_3 (Fig. 2) corresponding to the point 3 100 must act in the direction of the tangent of the circle B (Fig. 4). Accordingly let said force be laid down as P''_3 at the point 3 of Fig. 4^a perpendicularly to the line r_1 on a correspondingly reduced scale—*i. e.*, reduced 105 in the ratio of the radius of the circle B and of the length of the line r_1 . U is the circumferential force of the driving pin known by reason of the balanced diagram of work.

To the principle of the positive movements or of the known conditions of static and dynamic forces of the same correspond in the present case the parallelograms of forces shown in Fig. 4^a, while for the positive path k may be substituted the normal 110 N, *i. e.*, the force vertical on the path. The force available—*i. e.*, the circumferential force U—is subdivided in a known manner into the normals of the two paths to be considered, the positive path k and the travel 120 circle. These normals are: the force N just mentioned and the force Z_1 , which latter, as momentary static force, represents the journal pressure in the axis C of the travel circle. The force N is subdivided into the 125 forces P''_3 and Z_2 , which latter, as momentary static force, represents the journal pressure in the axis of oscillation. The work of the moving force U is equal to that of the force P''_3 , especially since other moving 130

forces are not acting. Of the above mentioned quantities of the parallelogram of forces only P''_3 , or the corresponding force at other points, and U are known. At each 5 point the direction of the normal N , or, which is equivalent, the angle of inclination β of the tangent T of the curve k to the direction of the circumferential force U , must be determined in such a manner that at the 10 respective point, according to the parallelogram of forces, the required driving power will result as component (in the example chosen, P''_3). The slot curve begins at the 15 point 0 of the travel circle M , and the different parts k of the curve, determined in accordance with Fig. 4^a, or the tangents T surrounding them at said point 0 or connected to one another, must of course be laid out by bringing the arc back through the 20 distances corresponding to the paths of oscillation traveled by the tool holder to the respective points of the travel circle, in order to obtain the connected curve to be constructed.

25 The above described method however appears somewhat lengthy. It is therefore preferable to use the other method of construction based on the partial strokes $\Delta l'_1$, $\Delta l'_2$, etc. The result is the same in the two 30 cases, since, owing to the constant product representing the work available at the driving pin, the determination based on the different forces corresponding to the transmissions must of itself show the required parts 35 of the stroke and vice versa.

For the mode of construction of the curve on the basis of the partial strokes two methods present themselves, an analytical-dynamic one and a geometric one. The latter 40 is simpler, but the former is more comprehensive in connection with Fig. 4, in which different positions and the below described angles are shown, and for that reason the former method of construction will be described first.

45 The different points of the curve K to be constructed (Fig. 4) all swing about the axis A . The point at which the driving pin comes into contact with the slot curve for the beginning of the movement at the point 1 of the travel circle must therefore lie on the arc a_1 , and in the initial position of the 50 curve at such a distance from the point 1 of the travel circle M that as soon as the loop reaches that point—i. e., intersects the circle M at said point—the tool holder will just have completed the first part of its stroke. Accordingly the point 1 of the circle M is connected with A , and at the point of intersection S of said connecting line 1— A with the arc B , the distance d_1 is laid out on the right, to which corresponds on the scale of the diagram of the work partial stroke $\Delta l'_1$, whereupon the right-hand end point S' of 65 the distance d_1 is connected with A . In ac-

cordance with the ratio of transmission between a_1 and B , the point of intersection of the line S' — A with the arc a_1 will then furnish the first point sought 1' of the curve K . The same applies to the remaining points, 70 but in order to keep the curve in the initial position the distance already traveled in each case must be taken into account, which is done in the following manner:

For the point sought 2', or the part 1'—2' 75 of the curve respectively, the movement on the part 1—2 of the travel circle is taken into account. For the construction of the initial position of the curve the part 1—2 of M must therefore be carried back on the 80 circles of oscillation a_1 and a_2 respectively until the lower end point of the same comes to lie at l' . For the purpose of thus carrying back the circle M relatively to K , the circle of oscillation drawn from the axis of 85 oscillation A with the radius AC is intersected from the point 1' with the radius r of the travel circle, whereby the point C_1 is obtained, and then from the latter with the same radius the arc 1'—2₀ is drawn. The 90 point 2₀ is then connected with A and the construction continued on the basis of the partial stroke d_2 in the same manner as described with regard to the point 1'. After the point 2' has been determined, the points 95 3₀ and 3' are determined from the point 2' in exactly the same manner as described with regard to the points 2₀ and 2'. The same applies to the remaining points 4', 5' . . . 13'. 100

In this manner the curve K is formed to the point 13', to which corresponds the point 13 of the travel circle M . As soon as the driving pin reaches the latter point, the curve coming into the position K' shown on 105 the left side of the figure, and the point of beginning O of the same coming to lie in the point O' of the circle of oscillation a_0 , the return stroke begins. In order to create a path for the latter, the point 13' of the 110 curve K may be connected by any line with the point of beginning of the same. In the example illustrated a straight line R has simply been used, which at the beginning of the return stroke comes to be in the position R' . 115

In Fig. 4 the different positions of the curve K are also indicated by small curve sections, i. e., by those parts of the curve K with which the latter intersects the travel 120 circle at the respective points 1, 2 . . . 12 of the forward movement of the driving pin. The relative angles of inclination of the curve K to the travel circle in these different positions in the course of the movement are 125 likewise shown. These angles concord with the angles between U and T , designated by β at the point 3, previously described in connection with Fig. 4^a for the mode of construction based on the distribution of forces. 130

These different angles, which may also be designated as working angles, show also in a characteristic manner the course of the drive according to the invention: They increase and decrease in inverse ratio to the forces P' in accordance with the diagram (Fig. 2)—i. e., they decrease in accordance with the diagram Δl (Fig. 1) or the partial strokes $\Delta l'_1$, $\Delta l'_2$, etc., (Fig. 2), reaching their minimum about the middle of the working stroke, where P' is maximum, and increase likewise in accordance with the values Δl .

It is obvious that the shape of the curve K is determined, among other things, by the choice of the point 13 of the travel circle, and that such choice may be made at will according to requirements. In other words, when the highest possible ratio is desired between the working stroke and the return stroke, it is possible to bring the point 13 as close to the point 0 as desired without interfering with the possibility of the above described construction of the curve K . It is merely the practical feasibility of construction, especially the necessity, existing in all cases, of providing a path, if ever so short, for the return stroke, that puts certain restrictions, though within very wide limits, upon the choice of the ratios between the working stroke and the return stroke.

It is to be noted that the first part of the curve K , at which the point 0 has a common tangent with the travel circle M , must under no circumstances be carried below the circle of oscillation a_0 . When it is desired to impart to the tool a still higher initial velocity, it is permissible to give the curve section between 0 and 1' an additional downwardly extending projection, e. g., in the manner indicated in dotted lines, but such projection, as stated, must not extend below a_0 , because the driving pin would in that case not be able to move the link and might cause breaks, especially since a_0 represents the prescribed lowest path of oscillation.

It is obvious that the loop KR according to Fig. 4, which forms a line closed within itself, can not be in the nature of a slot but must be in that of a groove or the like.

In Fig. 5 is shown the mode of construction of the curve in accordance with the simplest embodiment of the invention, which has already been briefly described in connection with Fig. 3. The curve K forms the geometric middle line of the slot 4 according to Fig. 3 and, in distinction from the curve KR of Fig. 4, does not constitute a closed path, but terminates, as will be seen, at a point corresponding to the highest point Z of the travel circle, which the driving pin reaches at the end of half a rotation, so that during the second half of the rotation the driving pin slides back in the same path.

In this case the path, not being closed, may

of course be either in the nature of a groove or in that of a slot.

In the loop according to Figs. 3 or 5 respectively, the curve of which up to the point 8_1 is constructed in exactly the same manner as the curve of Fig. 4, we have a simple arc-shaped slot readily applicable to all cases. But the fact must be taken into consideration that, as distinguished from the very exact solution according to Fig. 4, certain conditions undergo a change owing to the circumstance that the driving pin slides back in the same slot or along the same slot wall to the beginning of the return stroke. It is especially the course of the values Δl (Fig. 2) in the part of the working stroke following the point 8_1 , or the length of such part, as also the beginning of the return stroke, that can no longer be made directly to correspond exactly to the second half of the diagram; still less can these values be chosen at will, but are determined by the curve K itself, which is retained also for the second part of the working stroke. Thus the point 13 of the travel circle M , corresponding to the beginning of the return stroke, comes of itself to be the point of contact of the curve K (in its position K') with the travel circle. From this it follows that in certain cases the length of the stroke does not correspond to the length desired in the respective case but is greater, for instance, so that from the point 12 to the point 13, e. g., of the travel circle an idle stroke in the working direction will take place. The changed distribution of the parts 8 to 13 of the stroke is apparent from the circle of oscillation B of the tool holder; these parts no longer correspond accurately to the diagram of Fig. 2, nor does the point 7 any longer correspond to the middle of the stroke, so that the second part of the diagram actually resulting, as distinguished from Fig. 2, comes to be asymmetric to the first half.

But it may be stated that, aside from the fact that compliance with the first part of the diagram is frequently sufficient for practical purposes, we have in many instances (in the case of certain materials and classes of work) a very asymmetric diagram, so that the method of construction according to Fig. 5, which is distinguished by great simplicity, can in many cases be employed with perfect accuracy. With regard to other cases it may be stated that by the additional employment of further methods of improvement or intervention according to this invention, which will be hereinafter described (changeability of curve, employment of a secondary slot), all the inaccuracies connected with the simple slot according to Fig. 5 can be effectively compensated. It is true that in the combination of said slot with a secondary slot (Fig. 7) two links are required; still, in

many cases the employment of two simple slots will be preferable, for technological and mechanical reasons, to the employment of a long curved groove according to Fig. 4.

5 In order that the form of construction according to Fig. 5 may be effective, another requirement is that the curve K must lie not only above the circle a_0 , as in Fig. 4, but also above the common tangent t of the circles 10 M and a_0 , because otherwise (for dynamic and geometric reasons not to be described at length) upon the return stroke it will not be the lower end point but an intermediate point of the lower part of the curve K that 15 will return to the point 0 of the travel circle M, so that a certain lower part of the curve is left behind on the left side of the circle a_0 , and thus the desired method of operation will not be attained.

20 Although, as stated above, the point 13 of the travel circle, *i. e.*, the beginning of the return stroke, and hence the ratio between the working stroke and the return stroke, is determined by the curve K itself and can 25 therefore not be chosen at will, as in the method of construction according to Fig. 4, the invention renders it possible even in this case to secure a considerable improvement over former ratios between the working 30 stroke and the return stroke without materially affecting the shape of the slot constructed on the basis of the diagram. This method is illustrated in Fig. 6 and consists in the following:

35 K designates a slot according to Fig. 5 in the case of a ratio between working and return stroke which is normal from the standpoint of the invention, yet exceeds former ratios. In this case the ratio in question is

$$\frac{360^\circ - \alpha}{\alpha}$$

40 —*i. e.*, greater than the hitherto known maximum 3:1. When the radius of curvature of the lower part of the curve K, which at the beginning of the return stroke occupies the position K' and contacts at R with the travel circle M, is shortened so that, for instance, the curve K_1 will result, the contact point of the same with the travel circle will be at R_1 —*i. e.*, below the point R. The angle of the return stroke is then $\alpha_1 < \alpha$. This result, or even a better one, can be insured according to the invention also by other means, namely, by making the distance of the center C of the travel circle from the axis of oscillation A of the tool holder shorter in the manner illustrated, 45 *i. e.*, placing it, for instance, in the point C_1 . From this results, even for a normal curve K_2 , identical with the curve K, the return stroke angle $\alpha_2 < \alpha$. Even $\alpha_2 < \alpha_1$ can be attained.

50 65 It is obvious that by the combinatory ap-

plication of the two methods last above described, as illustrated by the curve K_3 and the angle α_3 , a very high measure of the ratio in question can be secured; in the example shown, $\alpha_3 < \alpha_2 < \alpha_1 < \alpha$. In the practical application a ratio of, *e. g.*, 7:1 and even above can be obtained without difficulty.

70 As briefly indicated above, a machine element swinging back and forth may be employed as driving device in place of a rotating eccentric pin. Such a form of construction is shown diagrammatically in Fig. 5^a, which is particularly suitable for hand operation. In this apparatus a lever 7 is capable of rocking on a shaft 8 mounted in the frame 75 and carries a pin 5. The latter engages in a slot in the lever 2 constituting the tool holder. In its forward stroke (working stroke) the hand lever 7 swings from its initial position shown through the angle α 80 into the position 7' indicated in dotted lines, and in its return stroke from the latter position through the same angle into the initial position. In this movement the pin 5 describes, in accordance with the same angle, 85 the travel arc M, which in the drawing is subdivided into 13 equal parts in a similar manner as in preceding examples. Corresponding to the different points 0, 1, 2 ... 13, the middle line of the slot in the lever 2, is 90 constructed on a different scale but in other respects in exactly the same manner as described in detail in connection with Fig. 4. It will be seen that in this case, as distinguished from previous forms of construction, 95 the path of movement lies within 180°, which is proper for advantageous operation of a hand lever—*i. e.*, the length of the travel path or of the slot respectively is still 100 shorter, other conditions being equal, than in the form of construction according to Fig. 5. With regard to the coaction of the driving pin with the walls of the slot or of the groove, the difference is that, while in the construction according to Fig. 4 the driving 105 pin slides along the inner wall of the groove up to 180°, beyond 180° along the outer wall and during the return stroke again along a part of the inner wall, and in the construction according to Fig. 5, during the entire 110 forward stroke along the inner wall in two directions, and during the return stroke along a part of the outer wall of the slot, in the construction according to Fig. 5^a, the movement of the driving pin during the 115 forward stroke is along the inner wall in one direction throughout, and during the return stroke along the entire outer wall of the slot, the working stroke being equal to the return stroke owing to the peculiar character of the oscillating movement in question. Hence the above described methods for improving the ratios between working 120 stroke and return stroke are not applicable 125 in this case, but over the form of construc- 130

tion according to Fig. 4 it has the advantage of a single short slot, and over the other form of construction according to Fig. 5, likewise simple, it has the advantage, aside from the still shorter slot, of accurately following the diagram of work (Fig. 2). Fig. 5^a shows how the invention may be carried out in very different cases, especially also for different kinds of drive, in accurate agreement with the principle of the diagram of work and also with a relatively very short path of travel.

Hence where no importance is attached to improving the ratio between working stroke and return stroke, the form of construction according to Fig. 5^a may be used to good advantage.

In the example shown the upper part of the slot has the characteristic shape of an inflection curve, which is due to the circumstance that in this case the driving pin, during the entire working stroke, including the last rapidly rising parts of the same (Fig. 2), coacts with the slot within 180°, while for instance, in the case of Fig. 4 the movement of the driving pin corresponding to the last parts of the stroke takes place beyond 180°, *i. e.*, on the other side, which in the example shown is apparent in the approximately symmetrical return of the curve K (Fig. 4) relative to the upper part of the slot according to Fig. 5^a.

In cases where $P'_{\max}$ (Fig. 2) corresponds to the end of the working stroke, hence where the diagram of work shows only a steadily ascending curve and not also a receding part (pressing or stamping work, riveting work, etc.), the upper inflection part shown in Fig. 5^a is dispensed with. The result is therefore a still simpler and shorter slot generally arc-shaped, so that this form of construction is applicable with still better results to the above mentioned cases.

In the example according to Fig. 5^a the outer wall of the slot, along which the return stroke takes place, is made parallel with the inner wall for the sake of simplicity, and this shape appears suitable in many cases also with regard to the course of the velocities during the return stroke. But of course the outer slot wall, here as well as in other forms of construction, may be given any desired form corresponding to the nature of the course of the return stroke required in each case.

In Fig. 7 is shown diagrammatically the general arrangement of a cutter (shears) arranged according to the invention for a secondary transmission briefly referred to above.

The essential feature of the same is that the rocking lever 2, which is again rotatably mounted on the shaft 6 in the frame 3 and actuated by the driving pin 5 by means of the primary slot 4, is not directly connected

with the movable shear blade 1, but engages by means of a driving pin 11 in a slot 12 in a second lever 9, *e. g.*, a bellcrank, likewise capable of rocking about its fulcrum 10 in the frame 3, which latter lever carries shear blade 1. To the stroke of the latter corresponds the angle β . While the second driving pin or driver 11 describes the angle 11, 11' around the axis 6, corresponding to its angle of deflection α determined by the slot 4, said pin sliding along the upper limiting line of the secondary slot 12, the longer arm of the lever 9 describes the arc 13, 11' about its fulcrum 10, to which corresponds the angle β . During the return stroke the driving pin 11 slides along the lower limiting line of the slot 12.

In the example according to Fig. 8 the mode of construction of a secondary slot, with simultaneous employment of the geometric method previously mentioned in connection with Fig. 4, is illustrated diagrammatically. For the sake of simplicity the second driver Z is also shown as a point. In the practical construction the secondary slot S as determined must of course be widened parallel with itself according to the diameter of the pin Z.

In the example according to Fig. 8 let it be assumed that the curve K serving as primary member does not accurately correspond to the diagram of work for the reasons stated in connection with Fig. 5, and that therefore, for this or some other reason, an improvement in the transmission or an intervention of some kind is to be brought about by means of a secondary slot. On the arc of oscillation B of the primary lever carrying the curve K, is shown the course 0, 1, 2 . . . 13 of the stroke sections, which course is brought about by said curve and for some reason does not correspond exactly (or in some cases but very little) to the diagram of work or to momentary requirements, while the exact course actually required 0, 1', 2', 3' . . . 13' of the stroke sections is shown on the arc of oscillation B₂ of the bellcrank lever (Fig. 7) rotatable about the axis C₁₀ and constituting the tool holder. The driving pin Z of the primary lever rotatable about the axis C₆ and engaging in the secondary slot S to be constructed, describes during the forward movement 0-13 of the main driving pin on the circle M the arc B₁, the radius and divisional points 1, 2, 3 . . . of which agree with those of the arc B. The different points 1, 2, 3, . . . of the secondary slot S must be determined geometrically in accordance with the requirement that, while the pin Z describes the stroke sections 0-1, 1-2, 2-3, etc., on the arc B₁, the tool holder must describe the stroke parts 0-1', 1'-2', 2'-3', etc., on the arc B₂. Consequently there is laid out at all points, in the same manner as most clearly

120
125
130

shown at point 13 of the arc B_1 , on the arc drawn through the points of the latter about the center C_{10} (paths of the points of the secondary slot), the distance x measured in 5 the arc (in the example, of point 13) from the radius drawn through the respective point (in the example through 13') of the B_2 from the center C_{10} , downward from the line t (initial position of tool holder). In 10 the same manner the points of the lower limiting line, corresponding in each case to the required return stroke, of the secondary slot S are determined. In the present case it has been assumed, for instance, that in 15 place of the course of the return stroke resulting from the primary curve K and indicated by the points 14, 15, 16 on the arc B , the course of the return stroke indicated by the points 14', 15', 16' on the arc B_2 is 20 desired.

In this manner any greater or less inaccuracy of the primary transmission may be entirely eliminated by a secondary, or, if desired to meet further requirements, by a 25 tertiary slot, etc., and it becomes possible, in the manner indicated above, by such additional slot to take into account any given special cases, or to affect the course of the working ratios at any given points and to 30 any given extent. In Fig. 9 the measure in which such influencing by a secondary slot is possible is very clearly illustrated in an example, the geometric method of construction being the same as that of Fig. 8.

35 In this case the curve S_1 represents the geometric middle line of a slot which would transmit the movement brought about by the primary curve K to the tool holder without any change, *i. e.*, with unchanged course 40 of the same. In this case therefore, which is chosen merely for the sake of explanation, the subdivision of the arc B'_2 agrees perfectly with that of the arc B or B_1 respectively, while S_2 represents the line of the desired 45 secondary slot which produces at the tool holder the stroke sections corresponding exactly to the desired diagram of work. For the sake of simplicity only that part of the secondary slot is shown which corresponds to 50 the working stroke, such slot having been constructed on the basis of the arc B_2 , subdivided in accordance with the desired diagram of work, the radius of which arc deviates however, for the sake of comprehensiveness, from that of the arc B'_2 , and the 55 length of which does not correspond in this case to the desired length of stroke, which however does of course not affect the method of construction, especially since the ratio of 60 subdivision is independent of the radius of the arc.

A comparison of the two curves S_1 and S_2 will at once show the measure of the influence of the secondary slot, as distinguished from the primary transmission, at

each point of the two parts of the working stroke. It will be seen that the secondary slot S , instead of being a flat curve S_1 (in certain cases it may also be a straight line) has in the present case a wave-like form, in 70 which the trough of the wave corresponding about to the first half of the working stroke, comes to lie below the line S_1 , while the crest of the wave, corresponding about to the second half of the working stroke, comes to lie 75 above the line S_1 .

As previously stated, by varying the shape of the secondary slot it becomes possible to intervene variably in the course of the working factors, as desired in special cases, either 80 for the entire stroke or for any given part of the same. An example in this particular is also diagrammatically indicated in Fig. 9. If greater speed is desired at the beginning of the working stroke, other conditions being 85 equal, the flat part S'_2 , being the first part of the curve S_2 , may be replaced by the part S_0 . For such different cases nothing more is required than to exchange the secondary 90 slot in the below described manner, retaining unvaried all the other parts of the machine.

A similar case arises when work is to be done on blanks in large numbers or in groups, where the general conditions remain 95 the same (same class of work, same blanks, same material, etc.), a change occurring merely with regard to certain dimensions, for instance, passing from the production of holes in a plate of a certain thickness to the 100 production of holes of larger diameter in a plate of less thickness, or vice versa. In this case the course of the work may be the same except that the length of the stroke is varied according to the lesser or greater 105 thickness of the plate. The variation in the length of the stroke may be brought about in a manner not new in itself by an adjustable arrangement of the driving pin 5 (Fig. 7) of the primary lever or of other parts, 110 *e. g.*, by a multiple adjustable lever 2, etc. But in accordance with the invention the length of the stroke is preferably varied in a simple manner by using a different secondary slot (or additional slots), as indicated, for instance, in Fig. 10, where again all the remaining parts may be retained unchanged, the only measure required being 115 the exchange of the slot.

According to Fig. 10, one passes, for instance, from the slot 12, previously used, to another slot 12', drawn in dotted lines, by exchanging in the below described manner a part of the lever 9, which slot 12', generally of the same shape, has a shorter radius of 120 curvature, so that the tool holder 9 or 1 respectively, instead of swinging out through the working angle β corresponding to the slot 12, will swing out through the smaller angle β' corresponding to the slot 12'. The 125 130

result is a shorter length of stroke, *i. e.*, a correspondingly higher transmission of forces.

The modifications or measures described in connection with Figs. 7 to 10 may of course also be applied to the case of a lever drive, after the manner of the embodiment according to Fig. 5^a, when some intervention in the course of the working stroke or 10 any part thereof, or a special course of the return stroke, etc., is desired.

As regards the exchange of the slot, either one or the other slot (primary, secondary, etc.,) or all the slots may be exchangeably 15 arranged, so that one and the same machine can be used for the most varied conditions of work, retaining the economic method of operation corresponding to the diagrams of the working factors.

20 In Figs. 11 and 12 an advantageous form of construction of the exchangeable arrangement of the slot—*e. g.*, a primary slot—is illustrated. Fig. 11 is a front view and Fig. 12 a section on line A—A of Fig. 11.

25 The slot 4 is formed in a special part 14 of the lever 2, which latter is recessed in accordance with said part 14. Such recess is preferably stepped (see the right side of Fig. 12) and the part 14 provided with a 30 corresponding circular flange 15, so that said part 14 can be countersunk in the lever 2. The countersunk part 14 may be secured by means of any releasable fastening device (screws, clamping springs, etc.). In the 35 example shown the part 14 is provided on one side with one or more projections 16 in the nature of threaded bolts capable of being secured to the lever by means of winged nuts 17 or the like. The winged nut is likewise 40 so arranged as to be countersunk in a circular recess the part 18' of which is located in the exchangeable part 14, while the other part 18'', adjacent to the part 18' and forming with the same a circle, is located in 45 the lever 2.

The drive described may also be used to good advantage for universal machine tools. Fig. 13 shows an example of such construction. In this example the primary rocking 50 lever 2 carries pins 11, 19 and 20 which engage in corresponding (secondary) slots 12, 21 and 22 respectively in rocking levers 9, 23 and 24 respectively, which are mounted in the machine frame 3, only partly shown, 55 and rotatable about pins 10, 25 and 26 respectively. The lever 9 constitutes the tool holder for a pair of shears 1, while the levers 23 and 24 are pivotally connected, *e. g.*, with the tool holders of a punching 60 machine X (not shown, merely indicated by an arrow) and of a vertically guided iron-shape cutter Y or the like.

In this manner the requirements for economic work, referred to in the beginning, 65 may be met in a very compact manner in a

single machine frame and by joint drive for various machine tools.

The subject of the invention may of course be varied in many ways as regards details of construction and application. In 70 place of an oscillating loop, (link,) a rotary loop (link) with curved slot may of course be used, or the two may be connected back of each other in a manner not new in itself or combined with each other in any 75 desired manner. In place of a slot, a groove or other kind of curved surface may be employed, as previously stated. To insure accurate operation, care must of course be taken to have all the movable parts suitably 80 mounted and guided. To secure rolling friction in place of sliding friction, the driving pins or drivers may be fitted with a roller, and the latter, or the slot, may be toothed or corrugated, etc.

Claims:

1. A machine, comprising a driving member, a tool operating member, and a variable driving connection between said members, said connection including coöperating parts, 90 so related that the rate of movement of said tool operating member will vary relatively to that of said driving member, the variation being such that substantially equal increments of work will be effected during 95 equal increments of movement of said driving member throughout the working stroke of said tool.

2. A machine tool comprising in combination, a driving member operating at a constant rate of speed and having a working capacity computed on the basis of the area of the diagram of work resistances, a tool-holder, and means for transmitting the motion of the driving member to the tool-holder, said transmitting means including parts so related as to cause the tool-holder to operate under a varying force in accordance with the varying resistance offered by the work.

3. A structure according to claim 2, in which the transmitting means includes a member having a slot which is curved in accord with the work-resisting factor and co-operates with the tool-holder.

4. A structure according to claim 2, in which the transmitting means includes a plurality of coöperating members, having slots by which they are operatively connected, and which are curved so as to move the tool-holder in accord with the work-resisting factor.

5. A structure according to claim 2, in which the transmitting means includes a member having a short curved slot, formed in such a manner as to move the tool-holder under a varying force in accord with the varying resistance of the work, and to return it quickly to initial position.

6. A machine, as specified in claim 1, in 130

- which the driving connection includes a swinging member, driven by said driving member, and forming a secondary driver for said tool operating member.
- 5 7. A machine, as specified in claim 1, in which the driving member is a constantly rotating body, having a driving element to engage curved surfaces of the member to be driven thereby.
- 10 8. A machine, as specified in claim 1, in which the coöperative parts of said driving connection comprise a contact element, carried by one of said members, and curved surfaces carried by the other, to be engaged thereby, the variation in the movements of said members being dependent upon the forms of said surfaces.
9. A machine, as specified in claim 8, in which the curved surfaces are of such form
- 20 as to cause a relatively large proportion of the movement of the driving member to be utilized for the working stroke of the tool, and a relatively small proportion for the return stroke.
10. A machine, as specified in claim 8, 25 having interchangeable parts, carrying curved surfaces, of different forms, to provide for work on different work pieces, as to which the respective resistances at different parts of the working stroke are different. 30
11. A machine, as specified in claim 6, having a plurality of tool operating members, operatively connected with said secondary driver, to be driven thereby.

In witness whereof, I have hereunto 35 signed my name in the presence of two subscribing witnesses.

Dr. ARMIN TETÉLENI.
